Des. 203,690
Patented Feb. 8, 1966

203,690

MEDICINE SPOON

Iva D. Smith, 2112 Mathews Ave.,
Redondo Beach, Calif.

Filed Apr. 12, 1965, Ser. No. 84,718

Term of patent 14 years

(Cl. D44—29)

FIG. 1 is a front elevational view of a medicine spoon showing my new design;

FIG. 2 is a side elevational view thereof;

FIG. 3 is a top plan view thereof;

FIG. 4 is a rear elevational view thereof; and

FIG. 5 is a bottom plan view thereof.

I claim:

The ornamental design for a medicine spoon, substantially as shown.
